UNITED STATES PATENT OFFICE.

ANTHONY SCHNEIDER, OF WHIPPANY, NEW JERSEY, ASSIGNOR TO SEIDENBERG & CO. (INC.), OF NEW YORK, N. Y., A CORPORATION OF NEW JERSEY.

LINED CIGAR-BOX.

1,268,163.

Specification of Letters Patent.

Patented June 4, 1918.

Application filed September 14, 1915. Serial No. 50,598.

To all whom it may concern:

Be it known that I, ANTHONY SCHNEIDER, a citizen of the United States, residing at Whippany, in the county of Morris and 5 State of New Jersey, have invented new and useful Improvements in Lined Cigar-Boxes, of which the following is a specification.

This invention relates to cigar boxes.

In the cigar trade cedar wood is recognized as having peculiar properties rendering the wood beneficial when used to hold cigars or tobacco. The constant growing demand for cedar wood has increased the cost of this wood, and consequently the cost of 15 the box tends to become an important item in the total cost of a box of cigars. In order to economize this wood in the construction of cigar boxes, it has been attempted to make the walls very thin, but in doing so, 20 the walls of the box lose their rigidity and there is a well defined limit in thinness permissible in such walls.

One of the objects of the present invention is to produce a cigar box which can be manufactured at substantially the same cost or 25 less cost than the present boxes constructed of cedar wood, but which will effect economy in the amount of cedar wood employed.

A further object of the invention is to 30 produce a cigar box which will have somewhat the effect of a humidor on the cigars which it contains, and operate in such a way that no moisture will be added or subtracted from the cigars, enabling the box to preserve 35 the contents in substantially the same condition they are in when placed in the box. With this end in view, I provide a metallic protecting shell and provide within it a cedar wood lining of sufficient thickness to 40 enable the pores of the wood to act as an equalizer for the moisture inside the metal shell. In this way the box will keep the cigars in their fresh condition.

A further object of the invention is to 45 construct such a box so that it may be readily fastened in a closed condition, and which can be readily opened in a very simple manner when desired.

Further objects of the invention will appear more fully hereinafter.

The invention consists in the general combination of parts and details herein-after described, all of which contribute to produce an efficient lined cigar box.

A preferred embodiment of the invention 55 is described in the following specification, while the broad scope of the invention is pointed out in the appended claims.

In the drawing,

Fig. 1 is a perspective of the complete 60 box embodying my invention and showing the same in its opened condition and empty.

Fig. 2 is a perspective of the metallic shell which forms the outer part of the 65 box and showing same in its opened position with all the cedar wood of the box removed.

Fig. 3 is a perspective showing details of the invention.

Fig. 4 is a vertical cross-section through 70 the complete box.

Fig. 5 is a horizontal cross-section taken through one corner of the box and further illustrating details of the invention.

Fig. 6 is a vertical section taken through 75 the forward edge of the lid section of the box and further illustrating details of the interlocking or fastening connection for holding the box closed. This view is upon a very much enlarged scale.

Fig. 7 is a section taken at the same point as that of Fig. 6 but showing simply the outer shell at the lid of the box.

In carrying out my invention, I prefer to provide a metallic shell comprising a body 85 section 10 and a lid section 11, and these parts are preferably connected together by a hinge connection 12, see Fig. 2. The body section has a bottom 13 and vertical side and rear walls 14 and a front wall 15. These 90 walls preferably have their upper edges turned in so as to form a rounded edge 16. As this shell is made of sheet metal, it is slightly resilient, and I make use of this property of the shell to hold the liner 17 in 95 place.

This liner 17 preferably comprises a bottom liner 18 of cedar wood and vertical side wall liners 19 which rest at their bottom edges on the bottom liner 18, see Fig. 100.

The liners 19^a for the front and rear walls of the shell preferably extend the full length of the interior of the shell, and their inner sides at each end lie against the ends of the end liners 19. The end liners 19 are cut rather full as to their length so that they will fit tightly in place. They may be readily slipped into the body shell

and then forced outwardly between the liners 19, and the resiliency of the body of the shell will then hold them in position.

The upper edges of the side wall liners 19 preferably extend above the upper edges of the side walls of the body of the shell. The lid section 11 is preferably provided with a lid liner 20 preferably formed of cedar wood and fitting neatly into position 10 under the lid section and between the side walls 21 of the lid section, and forming the lid of the complete cedar box.

As the vertical walls of liner 17 extend above the top plane of the body section and 15 into contact with liner 20, the external joint between the body section and lid becomes closed by the walls of liner 17. While this practically produces a wood-to-wood effect at the top of the box, an exceedingly de- 20 siious condition, it also practically prevents the use of special liner retaining means for the box walls, it being undesirable to provide metallic securing devices extending through the box and liner walls. Hence the 25 walls are sprung into place, an action which can be readily had as the top edges of the liners are not inclosed excepting by the closing of the lid.

I prefer to provide means for holding this 30 lid liner 20 in position, and for this purpose I prefer to punch out tongues 22 from the rear wall 23 and the front wall 24 of the lid section, and bend these tongues so that they project across the under edge of 35 the lid liner and hold it against the main wall of the lid.

The vertical walls 14 and 15 of the body section are preferably pressed outwardly so as to form a slight bead 25 extending longitudinally around the box and I also prefer to provide interlocking means between the lid section 11 and the body section 10 so as to hold the lid section closed. This is preferably accomplished by punching an 45 opening in the forward wall 24 of the lid section 11 and cutting out some of the material so as to form a tongue, and the material of this tongue is offset so as to form a shoulder 26 near its upper end which can 50 be very readily taken hold of with one's thumb or finger. I also form the forward wall 15 of the body shell with an outwardly projecting offset or shoulder 27. When the box is closed, the lower edge 28 of the opening in the wall 24 will engage over the offset or projection 27 and hold the lid closed.

In order to release the interlocking means, it is simply necessary to press the forward wall 15 of the body section 10 inwardly 60 until the shoulder 26 moves out of engagement with the edge 28. The resilient quality of the box enables this catch to be released in the manner described.

In order to give the box substantially the same external appearance as an ordinary

wooden cigar box, I prefer to attach to the outer side of the lid section 11 a cover formed of paper grained to simulate cedar wood, and if desired, the side walls of the body section 10 may likewise be covered with this paper, but if desired, the coloring necessary to simulate cedar wood may be lithographed directly onto the metal of the lid. In either case the box is trimmed and resembles closely in appearance a regular 75 cedar wood cigar box.

By constructing a box in the manner described, I am enabled to produce a cigar box which is equally strong or stronger than an ordinary cedar wood cigar box, and which has the desirable properties of an ordinary cedar wood box. At the same time it does not require as great a quantity of cedar wood to construct it.

By forming the interlocking connection 85 for holding the box closed in the metal shell, I avoid the necessity for making any attachments to the wooden part of the box, and furthermore the lid plate 29, being of metal, when the box is closed, exerts a pressure 90 throughout its entire area, insuring that the cedar lid liner 20 will fit closely against the upper edges of the side liners 19 throughout the entire perimeter of the box so that cigars can be packed and pressed in 95 it like any regularly constructed and nailed cedar cigar box.

It is understood that the embodiment of the invention set forth herein is only one of the many embodiments or forms the invention may take, and I do not wish to be limited in the practice of the invention nor in my claims to the particular embodiment set forth. And I may use any feature of my invention without the other features.

What I claim is:

1. A cigar box and humidor, comprising an outer metal casing and cover therefor, and an inner lining formed of a bottom and side pieces of cedar wood loosely placed in the 110 casing, and a top lining also of cedar in the cover, the whole being so arranged that the closing of the cover will bring the top lining against the side pieces forcing the side pieces together and against the bottom to 115 form a substantially air tight inclosure.

2. A cigar box and humidor, comprising an outer metal casing and a flanged cover therefor, and an inner lining formed of a bottom and side pieces of cedar wood loosely placed in the casing with the upper edges of the side pieces projecting above the edges of the casing, and a top lining also of cedar wood in the cover, the whole being so arranged that the closing of the cover will 120 bring the top lining against the side pieces and force said pieces together and against the bottom to form a substantially air tight joint, with the flanges of the cover projecting below the upper edges of the side pieces. 125

3. A cigar box and humidor, comprising an outer metal casing and cover therefor, and an inner lining formed of a bottom and side pieces of cedar wood loosely placed in the casing, with the upper edges of the side pieces projecting above the edges of the casing, and a top lining also of cedar in the cover, the whole being so arranged that the closing of the cover will bring the top lining against the side pieces forcing the side pieces together and against the bottom to form a substantially air tight inclosure, and interlocking means between the cover flange and the upper edge of the casing to hold the cover closed.

10 4. A combined cigar box and humidor, comprising an outer metal casing having a flanged cover, and a removable inner lining formed of a bottom and side pieces of

cedar wood loosely assembled within the 20 casing with the upper edges of the side pieces projecting above the upper edges of the casing, a cedar wood lid complementary to the lining, the said cover flange being of sufficient depth to embrace, when closed, the 25 upper marginal edges of the metal casing and thus force the loosely assembled side pieces together, and interlocking means between the cover flange and the upper edge of the casing to hold the cover closed.

30 In testimony whereof I have hereunto set my hand in presence of two subscribing witnesses.

ANTHONY SCHNEIDER.
